UNITED STATES PATENT OFFICE.

AUGUSTUS S. WHITEWAY AND JOSEPH SULLIVAN, OF BOISE, IDAHO.

INTEGRAL CURB AND GUTTER AND MEANS FOR INSTALLING THE SAME.

1,279,059.

Specification of Letters Patent. Patented Sept. 17, 1918.

Application filed July 22, 1916. Serial No. 110,747.

To all whom it may concern:

Be it known that we, AUGUSTUS S. WHITEWAY and JOSEPH SULLIVAN, citizens of the United States, residing at Boise, in the county of Ada and State of Idaho, have invented a new and useful Integral Curb and Gutter and Means for Installing Same, of which the following is a specification.

The object of our invention is to provide a novel integral curb and gutter of concrete; to provide novel and economical means for installing same; and to provide novel means for erecting, adjusting and removing a combined curb and gutter form. It is further our object to provide improvements in the combination and arrangement of parts hereinafter set forth.

We attain the objects of our invention by the mechanism illustrated in the accompanying drawings, in which—

Figure 1 is a front elevation of our curb and gutter form viewed from the gutter side; Fig. 2 is a transverse section through our integral curb and gutter and the combined curb and gutter form, on line 2—2 of Fig. 1, the gutter form member being shown in extended position by dotted lines; Fig. 3 is a perspective of curb form member 1; Fig. 4 is a perspective of gutter form member 2; Fig. 5 is a perspective of expansion joint member 3; Fig. 6 is a detail sectional view on line 6—6 of Fig. 2; Fig. 7 is a detail of one of the inner reinforcing plates 14 and countersunk bolts 13; and Fig. 8 is a perspective of an extension gutter form member 4 adapted to be interposed between members 1 and 2.

Like numerals designate like parts throughout the several views.

Referring to the accompanying drawings, we provide an angular gutter form member 1, adapted to adjustably engage with an angular gutter form member 2 by means of a suitable bolt 5, inserted through a horizontally-extending orificed portion 16 of member 1 and a horizontally-extending slotted portion 17 of member 2 as shown in Fig. 6, or, when a very wide gutter is required, member 1 may adjustably engage an angular slotted member 4 by means of bolt 5, and member 4 in turn engage member 2 by means of a like bolt 5, in similar manner. Suitable planks 6, 7 and 8 are secured to the upwardly converging sides 9 and 10 of form 1 and 11 of form 2, respectively, by means of suitable bolts 12 and 13 having

their heads countersunk as shown in Fig. 2. The heads of bolts 13 engage in a reinforcing metal plate or strip 14 countersunk in plank 7, as illustrated in Fig. 7. On the outer portions of planks 7 and 8 near the end of each section we provide outer metal reinforcing plates 15, as shown in Figs. 1 and 2, bolted to the planks. Member 1 is provided with an outturned orificed foot 18, and member 2 is provided with a similar outturned orificed foot 19. Forms 1 and 2 are secured to the ground by steel stakes 20, which are each provided with a handle portion 21 bent at an angle of approximately 100 degrees relative to the body of the stake, as illustrated. The steel stakes are one foot seven inches long with a handle about six inches in length. Suitable expansion joint members 3 are provided for each section at suitable distances apart in the form, the distance apart of these members determining the length of planks for form sections. Members 3 are provided with $\frac{1}{2}$ inch orifices 22 for lifting the expansion joint when the forms are removed. On the outer side of plank 7 is fastened a one inch by one inch wood screed 23 for the purpose of forming the shape of upper side of gutter. 24 designates the engineers' wooden stakes to indicate position for forms.

In erecting the forms, engineers' level stakes 24 are driven in place, and the planks, which are bolted to the iron forms, are rested directly on the engineers' stakes, thereby causing the curb and gutter when completed to be absolutely level and straight. The adjustable engagement of forms 1 and 2 (or of forms 1, 4 and 2, when member 4 is used for a wide gutter) makes it possible to readily secure the form in place at any usual desired width. By reason of the convergent disposition of the sides 9, 10 and 11 of the form members 1 and 2, our forms can be lifted and removed easily and without injury to the concrete in the curb and gutter. This construction constitutes a great advantage over other forms, as the top of the curb and gutter is finished before our forms are removed from the concrete so that the finished lines are perfect, which is not true of other combined forms. Our entire form can be removed in one operation and in whole, and it is then immediately ready to replace without rebuilding again. Our forms 1 and 2 are placed a little over three

feet apart, three to each section. They are readily secured in place by steel stakes 20, and there is no hammering or pounding of the forms after they have been placed on the engineers' stakes. Consequently there is no difficulty in keeping the forms in perfect alignment. The stakes 20 are readily withdrawn by means of the handles 21. The partitions or expansion joint members 3 extend from the grade line up through and to a point one inch above top of curb and gutter. Orifices 22 are positioned in the margin of members 3 to make possible the convenient removal of these members after the sectional forms have been removed, without injury to the concrete. Members 3 are preferably of galvanized iron. With this form the concrete for both curb and gutter is held and formed until the concrete is set, forming an integral curb and gutter. When a block or street is three hundred feet long the contractor will require 640 feet of forms and two workmen to handle the output of a concrete mixer of eighty cubic yards capacity, as against eleven workmen required to install the same amount of curb and gutter by former methods. Also an important saving of time is effected in installing the forms after the engineers' level stakes are driven, as two workmen can place in position one thousand feet of these forms in nine hours.

All that is required of our form to set it is to place a chalk line on the outer edge of the iron frame at each end which gives a perfect alignment longitudinally, and resting the form on the engineers' stakes gives the proper alignment for the top of curb and gutter and does away with the leveling of ground required with forms heretofore devised. Form sections can easily be lengthened or shortened if desired, and their adjustability simplifies the construction work greatly.

What we claim is:

A combined curb and gutter form, comprising curb form members having upwardly convergent orificed sides, horizontally extending angular arms secured to the forms, gutter form members having the side thereof convergent to permit of ready removal of the form from the concrete, a horizontally extending angular arm secured to the gutter form, fastening means for securing the aforesaid arms in the desired adjusted relation, and planks permanently secured to the form members.

AUGUSTUS S. WHITEWAY.
JOSEPH SULLIVAN.
